UNITED STATES PATENT OFFICE.

LOUIS HECK, OF NEWARK, NEW JERSEY.

DISPENSING DEVICE.

1,244,205.

Specification of Letters Patent. Patented Oct. 23, 1917.

Application filed April 27, 1916. Serial No. 93,844.

To all whom it may concern:

Be it known that I, LOUIS HECK, a citizen of the United States, residing at Newark, in the county of Essex and State of New Jersey, have invented certain new and useful Improvements in Dispensing Devices; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in dispensing devices; and, the present invention has reference, more particularly, to a novel attachment, in the form of a support for a receptacle or can containing soap-powder, or a liquid soap, or the like, adapted to be attached in proper location, usually above the wash-basins in lavatories, bath-rooms, and the like.

The present invention has for its principal object to provide a novel and simply-constructed receptacle or can-supporting attachment for the purposes above stated, the support comprising a normally closed valve-like element mounted in a supporting receptacle or can-receiving support, and means for retaining the receptacle or can in its proper position for use, the said means at the same time being provided with a clamping or holding lever having a piercing element for piercing the sealed ends of the container or can, prior to securing the latter in its operative position upon or within the receptacle or can-supporting attachment.

The present invention has for its further object to provide an efficient and easily manipulated device of the character herein stated, which, furthermore, is neat and ornamental in appearance, and is perfectly sanitary.

Other objects of this invention not at this time more particularly enumerated will be clearly understood from the following detailed description of the present invention.

With the various objects of the present invention in view, the said invention consists, primarily, in the novel dispensing device hereinafter set forth; and, the invention consists, furthermore, in the novel arrangements and combinations of the various devices and parts, as well as in the details of

the construction of the said parts, all of which will be fully described in the following specification, and then finally embodied in the clauses of the claim which are appended to and which form an essential part of 60 the said specification.

The invention is clearly illustrated in the accompanying drawings, in which:

Figure 1 is a front elevation, and Fig. 2 a top or plan view of a dispensing device 65 showing one embodiment of the principles of the present invention.

Fig. 3 is a transverse vertical section of the device, said section being taken on line 3-3 in said Fig. 2; and Fig. 4 is a horizontal section taken on line 4-4 in Fig. 1, the valve-like dispensing element being represented in its normally closed relation, said view illustrating in connection therewith, and in plan, a metallic clamp for producing 75 the said normally closed condition of the said valve-like member or element.

Fig. 5 is a similar view of the parts illustrated in said Fig. 4, but showing its clamp operated and the said valve-like element in 80 its opened condition to permit of the dispensation of the regulated and required amount of the soap-powder or liquid soap from within the container or can into and through the said valve-like element.

Fig. 6 is a detail view, showing in elevation, certain of the receptacle or can-retaining or holding elements, looking in the direction of the arrow α in Fig. 1; and Fig. 7 is a plan of a fragmentary portion of one 90 of the can-heads and a cross-section of the piercing element, said view illustrating the pierced condition of the said head, when the container or can is mounted in its clamped relation, for use, upon the main supporting 95 structure of the device.

Similar characters of reference are employed in all of the said above described views, to indicate corresponding parts.

Referring now to the several figures of the 100 drawings, the reference-character 1 indicates a suitable bracket or support, usually provided with a base, as 2, for securing the said bracket to a wall 3, or the like, by means of screws 4, or other suitable fastening devices. The said bracket 1 is preferably cut-away, as at 5, and has secured thereto, by means of rivets, pins, or screws 6, a disk or plate 7 formed with an upwardly extending annular marginal flange 8, substantially of 110

the arrangement and construction shown in Figs. 1, 2 and 3 of the drawings, for the purpose of providing a support for and receiving a receptacle or can, as 9, containing 5 soap-powder, or a liquid soap, or the like.

The said disk or plate 7 is provided with a central opening or hole, as 10, in which is disposed a suitably formed nozzle-element, as 11, the same being supported in the said 10 opening or hole 10 by means of its annular flange 12, as shown in Fig. 3 of the drawings. This annular flange 12 provides a suitable seat for a correspondingly formed 15 annular flange-like member or portion 14 of a short flexible tube 13 which is made of rubber, or other suitable material which is readily compressible. This flexible piece of tubing is suitably disposed within the said nozzle-like element 11, as shown in said 20 Fig. 3, the said nozzle-like element 11 being formed in its opposite sides with cut-away or open portions, as 15, and in its lower end-portion having a suitable outlet, as 16.

Referring now more particularly to Fig. 25 1 of the drawings, it will be seen that there is secured to the bottom of the previously mentioned disk or plate 7, by means of rivets or other suitable fastening means 17 a pair 30 of plate-like members, as 18 and 19, the said member 18 being provided with an upwardly extending post-like portion 20, and the said member or element 19 being also provided with an upwardly extending post-like portion 21. Suitably secured to the 35 member or element 18 is a suitable stud or post, as 22, extending in a downward direction and secured to said post, as at 23, is a suitable metallic clamp which comprises a pair of arms 24 and 25 which are bent, as at 40 26, and are formed with a pair of manipulating members, as 27. The normal tendency of this clamp is to have its arms 24 and 25 suitably compress the flexible tube-like element 13, so as to shut off the interior of 45 the said tube, the said arms 24 and 25 extending into and passing through the previously mentioned cut-away portions or openings 15 in the said nozzle-like element. By pressing with the fingers upon the ends 50 27 of this clamp, the arms 24 and 25 are brought into the positions, indicated in Fig. 5 of the drawings, thereby allowing the compressed portions of the flexible tube 13 to expand and assume the position shown in 55 said Fig. 5, and permitting the powder or liquid from the previously pierced bottom of the receptacle 9 to pass into the said tube 13 and flow from the outlet 16 of the element 11. It is evident that by this arrangement 60 the amount of liquid may be regulated. As soon as the operator removes the fingers from the end-portions 27 of the clamp, the parts will again assume the positions indicated in Fig. 4 of the drawings, whereby the 65 flexible tube again becomes compressed and

shuts off any further supply from the can or receptacle 9.

The previously mentioned upwardly extending portion 20 has pivotally connected with its upper end, by means of a loop, as 70 29, an arm or rod 28, the said arm or rod 28 extending directly across the upper end of the can or receptacle 9, and being provided with an extension 30 which extends downwardly from the said arm or rod 28, at the free end-portion thereof. Suitably connected with the central portion 31 of the said arm or rod 28 is an inverted cone-shaped protector-element, as 32, which is formed with suitably disposed perforations or holes 75 33, and likewise secured to the said portion 31 of the arm or rod 28 by means of its rivet-end 34 is a piercing-element, as 35, which is readily forced through the sealed end 36 of the can or receptacle 9, as will be clearly evident. The said arm or rod 28 is also capable of a slight lateral movement, whereby the sharp knife-edge 37 of the piercing-element 35 can be employed to rip the sealed 80 end 36 sufficiently, so as to provide the said end with an opening, as 38, substantially as illustrated in Fig. 7 of the drawings. The said piercing element 35 may also be used for piercing the opposite end of the can or receptacle 9 prior to the disposition of said 85 end upon the disk or plate 7 and above the flexible tube 13.

The upwardly extending portion 21 of the member or element 19 is provided at its 90 upper end with a receiving slot or opening, as 39, into which the free edge-portion of the said arm or rod 28 is slipped, when producing the opening 38, and is suitably held in said slot 39. The parts are constructed in such a manner that when the edge of the 95 said arm or rod 28 is forced into said slot 39, the can or receptacle 9 will be suitably forced down upon the annular edge or flange 100 14 of the flexible tube 13 so as to provide a perfect closure which surrounds the previously formed opening in the opposite sealed end of the can or receptacle 9, as will be clearly understood from an inspection of 105 Figs. 1 and 3 of the drawings. The said upwardly extending portion 21 may also be 110 provided with a transversely extending flange-like member 40, the said members 30 and 10 serving as suitable finger-pieces for the proper manipulation of the said arm or rod 28. The said members 30 and 40 may 115 also be perforated, if desired, as at 41, for the reception of a suitable padlock, by means of which the parts are suitably locked in their assembled relation, to prevent the removal or theft of the can or receptacle 9. 120

From the foregoing description of the present invention it will be clearly seen that I have produced a simply constructed receptacle or can-supporting attachment which can be readily manipulated, is perfectly 125 130

clean, and therefore sanitary. The arrangement of the parts, furthermore, is such that there will be no clogging of the compressible tube-like member or element 11, and the device is at all times operative.

I am fully aware, that changes may be made in the general arrangements and combinations of the several devices and parts, as well as in the details of the construction of the said parts, without departing from the scope of the present invention as set forth in the foregoing specification and as claimed in the clauses of the claim which are appended to the said specification. Hence, I do not limit my present invention to the exact arrangements and combinations of the several devices and parts as described in the said specification, nor do I confine myself to the exact details of the construction of the said parts as illustrated in the accompanying drawings.

I claim:—

1. A dispensing device comprising a main support, a valve-element connected with said support, post-like members extending upwardly from said support, one of said post-like members being formed at its upper end-portion with a receiving slot, a clamping arm pivoted at one end to the other post-like member and adapted at its other end to enter said receiving slot to be thereby brought into retaining engagement with said slotted post-like member, and a piercing element connected with said clamping arm for piercing the sealed end of the can simultaneously with the clamping of the can upon said main support.

2. A dispensing device comprising a main support, a valve-element connected with said support, post-like members extending upwardly from said support, one of said post-like members being formed at its upper end-portion with a receiving slot, a clamping arm pivoted at one end to the other post-like member and adapted at its other end to enter said receiving slot to be thereby brought into retaining engagement with said slotted post-like member, a piercing element connected with said clamping arm for piercing the sealed end of the can, and a cone-shaped perforated protecting hood also connected with said clamping arm, said hood being secured to said arm so as to inclose said piercing element and to protect the opening formed in the can.

3. A dispensing device comprising a main support formed with an opening, a nozzle-element extending downwardly from said support, a compressible tubular member within said nozzle-element and having its one end-portion arranged within the opening in said main support, said nozzle-element having open portions in its opposite sides, and a clamp secured to said main support, said clamp having arm-portions ex-

tending into the open portions of said nozzle-element and normally compressing the said tubular member.

4. A dispensing device comprising a main support formed with an opening, a nozzle-element extending downwardly from said support, a compressible tubular member within said nozzle-element and having its one end-portion arranged within the opening in said main support, said nozzle-element having open portions in its opposite sides, a clamp secured to said main support, said clamp having arm-portions extending into the open portions of said nozzle-element and normally compressing the said tubular member, means also connected with said main support for clamping a can in its operative relation upon said support and directly over the said compressible tubular member, and a piercing element connected with said clamping means for piercing the sealed end of the can simultaneously with the clamping of the can upon said main support.

5. A dispensing device comprising a main support formed with an opening, a nozzle-element extending downwardly from said support, a compressible tubular member within said nozzle-element and having its one end-portion arranged within the opening in said main support, said nozzle-element having open portions in its opposite sides, a clamp secured to said main support, said clamp having arm-portions extending into the open portions of said nozzle-element and normally compressing the said tubular member, post-like members extending upwardly from said main support, one of said post-like members being formed at its upper end-portion with a receiving slot, a clamping arm pivoted at one end to the other post-like member and adapted at its other end to enter said receiving slot to be thereby brought into retaining engagement with said slotted post-like member, and a piercing element connected with said clamping arm for piercing the sealed end of the can simultaneously with the clamping of the can upon said main support.

6. A dispensing device comprising a main support formed with an opening, a nozzle-element extending downwardly from said support, a compressible tubular member within said nozzle-element and having its one end-portion arranged within the opening in said main support, said nozzle-element having open portions in its opposite sides, a clamp secured to said main support, said clamp having arm-portions extending into the open portions of said nozzle-element and normally compressing the said tubular member, post-like members extending upwardly from said main support, one of said post-like members being formed at its upper end-portion with a receiving slot,

a clamping arm pivoted at one end to the other post-like member and adapted at its other end to enter said receiving slot to be thereby brought into retaining engagement with said slotted post-like member, a piercing element connected with said clamping arm for piercing the sealed end of the can, and a cone-shaped perforated protecting hood also connected with said clamping arm, 10. said hood being secured to said arm so as

to inclose said piercing element and to protect the opening formed in the can.

In testimony, that I claim the invention set forth above I have hereunto set my hand this 25th day of April, 1916.

LOUIS HECK.
